BY *John A. Macmillan*
ATTORNEY

Patented Oct. 5, 1926.

UNITED STATES PATENT OFFICE.

WILLIAM E. LAURA, OF SAN JOSE, CALIFORNIA.

AUTOMOBILE WINDOW SHADE.

Application filed December 10, 1925. Serial No. 74,547.

This invention relates particularly to a shade of the roller type mountable on the exterior of a machine and just over the window to be shaded.

5 It is one object of the invention to provide a shade of the character indicated that will effectually shield the eyes of occupants of the car without materially interfering with their normal field of vision.

10 It is another object of the invention to provide a shade that may be readily extended or retracted as desired and means for effectually bracing it against vibration when in an extended position.

15 It is still another object of the invention to provide a device of the character indicated that will be simple in construction, economical to manufacture, easily applied or affixed upon an automobile, and highly efficient in its practical application.

In the drawing,—

Figure 1 is a front elevation of the device.

Figure 2 is a perspective illustration of the device in position over an automobile 25 door window.

Figure 3 is an enlarged end elevation of the device.

Figure 4 is a detail perspective of one of the braces.

30 Referring more particularly to the drawing, I show at 1—1 the two end brackets of the device, these brackets being mounted upon the automobile, one at each side of the window to be protected, in any suitable manner

35 as by screws 2. These brackets 1—1 are spaced and supported by a wood visor element 3 shaped and formed as indicated in dotted lines in Figure 3 and to which the brackets are fastened by means of screws 4.

40 Between the brackets 1—1 and under the visor 3 is mounted an ordinary shade roller 5 fitted with the usual spring and detent mechanism. These details of the roller are not shown in the drawing as they are a part

45 of the roller itself as it is placed on the market. On the roller is mounted a short piece of suitable flexible material, preferably of the same material as used for covering the top of the machine, as shown at 6.

50 The outer end of this sheet 6 is attached to a rod 7.

At the lower end of each bracket 1 is pivotally mounted an arm 8, and between the outer ends of the two arms 8—8 is secured the rod 7. The normal position of the arms 8—8 is within the brackets 1—1 and

with the flexible visor 6 rolled up on the roller 5. In this position the device is inconspicuous and, in fact, improves the appearance of the automobile. To render the device operative as a shade it is only necessary to swing the rod 7 outwardly and downwardly about the pivotal mounting 9, the normal operation of the roller serving to permit the shade to remain extended as desired, under normal conditions.

To insure the shade from jarring loose or vibrating unduly, I provide a means for bracing the rod 7 against the brackets 1—1 and against the pull of the spring in the roller 5.

This means comprises an arm 10 pivotally mounted on each arm 8 and near the lower end thereof as at 11. The free end of each arm 10 is formed into a pair of oppositely directed grooves as 12—13 so that when the shade is rolled up each bracket 1 will engage the groove 12 in the arm 8 mounted thereon and the arm 8 will engage the other groove 13. By means of this construction when the arm 8 is folded into the bracket 1 its engagement therewith as described renders it easily accessible for extending when the shade is extended, and the engagement of the arm 8 with slot 13 prevents it from collapsing too far into the device. By grasping the upper ends of the two arm 10—10 the shade may be extended without touching the rod 7 or the shade mounted thereon.

90 In the forward edge of each bracket 1 is formed a notch 14 so that when the shade is extended the upper end of the adjacent arm 10 may be slipped into this notch and the shade braced against the pull of the spring in the roller and effectually held against movement.

95 It may be readily seen from the foregoing description that I have provided a shade that is highly efficient in its practical application because it effectually shields the eyes of the occupant of the car without interfering with his field of vision. The lower edge of the visor being spaced a distance from the window through the action of arms 8—8 the view is not nearly so much obstructed as would be the case if the shade drew down vertically.

100 This device is particularly useful in mountain driving, and in driving in the early morning or in the evening when the sun is low. It can be readily affixed to any auto-

mobile, and is highly useful in storms, because it shields the window from falling rain or snow, keeping the window clear if closed and preventing the rain or snow from entering the car if the window is open.

It is to be understood, of course, that while I have herein shown and described the preferred embodiment of my invention, changes in form, construction and method 10 of operation may be made within the scope of the appended claims.

I claim:—

1. A shade comprising a pair of opposed brackets, a roller shade operatively mounted 15 therein, an arm pivotally mounted on each bracket and engaging the shade of said roller shade, and a brace pivotally mounted

on each arm at one end, its other end having oppositely directed grooves formed therein for engaging the bracket and arm when collapsed. 20

2. A shade comprising a pair of opposed brackets having notches formed in one edge thereof, a roller shade operatively mounted therein, an arm pivotally mounted on each 25 bracket and engaging the shade of said roller shade, and a brace pivotally mounted on each arm at one end, its other end being adapted to engage a notch in the bracket when the shade is extended and having oppositely directed grooves formed therein for 30 engaging the bracket and arm when the shade is retracted.

WILLIAM E. LAURA.
